METHOD OF PRINTING

Francis Jack Jeuck, Battle Creek, Mich., assignor
to The International Printing Ink Corporation,
New York, N. Y., a corporation of Ohio

Application December 27, 1935, Serial No. 56,303

8 Claims. (Cl. 101—416)

This invention relates to a method of printing and more particularly to a method of setting ink on printed material.

My method contemplates the use of an ink containing a solvent whose vapors are inflammable and includes the step of igniting and completely or partially burning the vapor of the solvent in the ink after the ink has been printed on paper or other material. The method has the advantage of causing a more rapid setting of ink than has heretofore been obtainable, and also of chemically destroying the solvent in the ink so that it cannot resoften the ink after it has been set. Furthermore, I have discovered that ignition and burning of the ink vapor may be carried out without scorching or burning combustible material such as paper to which the ink has been applied.

In the accompanying drawing, I have shown diagrammatically an apparatus which may be used for carrying out my method. To more fully explain the nature of my invention, I will describe a specific method embodying it which may be carried out by means of the apparatus indicated in the drawing.

The drawing shows diagrammatically a typographic printing press of any ordinary construction in which one or more printing inks are applied to a traveling web of paper, the usual rewind roll on which the printed web is wound after printing, and a steam-heated roll over which the web passes between the press and the rewind roll. The ink is applied by the press to the side of the web which is uppermost as the web leaves the press, so that the back or unprinted side of the web is in contact with the heated roll. Adjacent to the web between the heat roll and the rewind roll is a row of Bunsen burners extending across the web and directing gas flames against the printed side of the web. One of the Bunsen burners is shown at A in the drawing.

The ink used in my method, when applied to typographic printing, has a vehicle consisting wholly or in part of a colloid which serves as a thickener and binder dissolved in a solvent which is practically non-volatile at ordinary press room temperatures (20° to 25° C.), and which is rapidly converted into an inflammable vapor at the temperature of steam or slightly superheated steam (100° to 150° C.). Known inks of this character include those whose vehicles consist of low-viscosity nitrocellulose dissolved in diethylene glycol monobutyl ether (butyl carbitol).

In carrying out my method with such an ink and with apparatus such as that indicated in the

drawing, the ink solvent remains liquid in the press which is operated at ordinary room temperature (20° to 25° C.), so that substantially no drying of the ink occurs on the rollers or plates of the press. As the web passes over the heated roll, it is raised to a temperature at which the solvent vaporizes rapidly. Solvent vapor, therefore, rises from the web and beyond the heat roll and the air overlying the web becomes mixed with the vapor. The vapor is ignited by the gas flames from the burners A, and being mixed with air the vapor burns very rapidly or "flashes". The vapor flashes so rapidly that the flame of the burning vapor extends only a short distance along the web. Any flame which may extend as far as the rewind roll is snuffed out as the web is wound up on this roll.

An important and unexpected feature of this process is that the web of paper is not burned or scorched although the temperature of the burning vapor is obviously high enough to scorch and burn paper. Without binding myself to any theory, I attribute this important result to the great rapidity with which the vapor when mixed with air burns or flashes.

While inks such as those to which I have referred may be set by volatilization of the solvent only, I have found that my ignition method results in a much more rapid setting than has been heretofore obtainable. Thus, in the apparatus illustrated, the ink is perfectly set when the web travels at a high speed, such as 400 feet per minute. Furthermore, in my process the danger of resoftening the ink by condensation of the solvent vapor upon the printed matter is eliminated by the chemical destruction of the solvent involved in the combustion of the solvent vapor.

Complete combustion of all the solvent vapor from the ink is probably not obtained in my method; and I have ascertained that the success of the method is not dependent upon actually burning all the vapor, but requires only that the vapor be ignited and that at least a part of it be flashed or burned.

My invention is not limited to use of the particular sort of ink, nor to the particular type of printing (typographic), which has been described in the specific method, but may be practiced advantageously in the use of any ink containing a volatilizable liquid whose vapor is inflammable, whether said ink be applied to a web or other sort of sheet.

What I claim is:

1. In a method of printing which comprises applying to a sheet a printing ink containing a

5 volatilizable liquid whose vapor is inflammable and thereafter vaporizing said liquid in the ink on the sheet, the step which consists in igniting the vapor of said liquid as it emerges from the ink on the sheet so that the vapor is at least partially burned in immediate proximity to the sheet.

10 2. The method of printing which comprises applying to a combustible sheet an ink containing a volatilizable and inflammable liquid, and thereafter volatilizing said liquid while the sheet is exposed to the air so that the vapor emerging from the ink on the sheet becomes mixed with the air overlying the sheet, and flashing said mixture 15 in the immediate proximity of the sheet.

15 3. The method of setting a printing ink containing a volatile and combustible substance, which comprises volatilizing, igniting and partially burning said substance in the immediate 20 proximity of the printed matter.

20 4. The method of printing which comprises applying an ink containing a volatilizable, inflammable liquid to a traveling web, heating the 25 web at a point in its travel to volatilize said liquid, and igniting the vapor as it emerges from the ink on the web.

25 5. The method of printing which comprises applying an ink containing a volatilizable, inflammable liquid to a traveling web, heating the 30 web at a point in its travel to volatilize said liquid, and igniting the vapor emerging from the

ink on the web, and snuffing out the flame by winding up the web.

6. In the method of printing which comprises applying to a sheet a printing ink whose vehicle contains a thickening agent dissolved in a volatilizable and inflammable solvent liquid which is stable at ordinary press room temperatures and thereafter vaporizing said solvent liquid in the ink on the sheet, the step which comprises igniting the vapor of said solvent as it emerges from 10 the ink on the sheet, so that the vapor is at least partially burned in immediate proximity to the sheet.

7. The method of printing which comprises applying to a combustible sheet an ink whose 15 vehicle contains a thickening agent dissolved in a volatilizable and inflammable solvent liquid which is stable at ordinary press room temperatures, and thereafter volatilizing said solvent liquid while the sheet is exposed to the air so 20 that the vapor emerging from the ink on the sheet becomes mixed with the air overlying the sheet, and flashing said mixture.

8. The method of printing which comprises applying to a traveling web an ink whose vehicle 25 contains a thickening agent dissolved in a volatilizable, inflammable solvent liquid which is stable at ordinary press room temperatures, heating the web at a point of its travel to volatilize said solvent liquid and igniting the vapor as it 30 emerges from the ink on the web.

FRANCIS JACK JEUCK.
